(57) **CLAIM**

The ornamental design for a card protector, as shown and as described.

DESCRIPTION

FIG. 1 is a front perspective view of a card protector in a closed position in accordance showing my new design.

FIG. 2 is a front perspective view in an open position thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The evenly spaced broken lines in the drawings depict portions of the card protector that form no part of the claimed design.

1 Claim, 7 Drawing Sheets
